UNITED STATES PATENT OFFICE.

WARREN McARTHUR, JR., OF CHICAGO, ILLINOIS, ASSIGNOR TO R. E. DIETZ COMPANY,
A CORPORATION OF NEW YORK.

TUBULAR LANTERN.

1,218,428.

Specification of Letters Patent.

Patented Mar. 6, 1917.

Application filed January 17, 1914. Serial No. 812,695.

To all whom it may concern:

Be it known that I, WARREN McARTHUR, Jr., a citizen of the United States, residing at Chicago, in the county of Cook and State 5 of Illinois, have invented a new and useful Improvement in Tubular Lanterns, of which the following is a specification.

This invention relates to that class of tubular lanterns in which the globe is 10 mounted in the lantern frame by a metallic chimney which bears upon the globe and is movable up and down in the upper portion of the lantern frame. A lantern of this 15 general type is shown, for instance, in my Letters Patent No. 1,070,152, dated August 12, 1913.

The object of this invention is to improve the construction of the metallic chimney and connecting parts with a view of reducing 20 the height of the lantern without impairing its burning qualities, and of rendering the lantern more convenient in operation.

In the accompanying drawings:

25 Figure 1 is a front elevation of a tubular lantern provided with these improvements.

Fig. 2 is a side elevation of the lantern showing the globe tilted back.

Fig. 3 is a fragmentary sectional elevation, on an enlarged scale, of the upper portion of a lantern at right angles to Fig. 1.

Fig. 4 is a similar view showing a modified construction of the metallic chimney.

Fig. 5 is a fragmentary side elevation of 35 the lantern top partly in section, showing a modified construction of the upper end of the chimney.

40 10 represents the oil font, 11 the lower air chamber, 12 the tubes and 13 the upper air chamber, all of any suitable construction.

45 14 represents the globe which rests upon the usual plate 15 and is detachably held thereon by the wire guard 16, or any other suitable holding device. The globe plate 17 may be hinged to the lower part of the lantern frame so that it can be tilted back with the globe when the chimney is raised, as represented in Fig. 2.

50 17 represents the cylindrical portion of the metallic chimney which is vertically movable in the upper portion of the lantern frame, and 18 represents the base flange of the chimney which bears upon the globe when the latter is in its normal position.

This base flange is substantially flat or 55 horizontal, forming a flat cover for the upper end of the globe, and the cylindrical portion of the chimney rises centrally from this flat base flange.

The base flange rests with its marginal 60 portion 19 upon the globe and for the purpose of enabling the chimney and the globe to readily center themselves on each other upon lowering the chimney, the marginal portion of the base flange is constructed to 65 enter the globe, for instance, as represented in Fig. 3, where the marginal portion of the base flange is shown as being provided on its under side with a depending annular lip 20 which enters the globe. If desired, 70 the base flange may be constructed on the under side of its marginal portion with an annular depression 21, Fig. 4, by means of which the flange engages the upper end of the globe.

75 22 represents the transverse lifter shaft which is journaled on the upper portion of the lantern frame and passes through slots 23 in the cylindrical portion 17 of the chimney. These slots are preferably arranged 80 near the base flange.

The flat base flange is to a certain extent yielding or springy and yields to the pressure of the lifter shaft in seating the base flange upon the globe and the latter upon 85 the globe plate by means of the lifter shaft. This spring action of the base flange serves to hold the lifter shaft securely in the locked position and also enables the parts to adapt themselves within certain limits to globes 90 of different heights, the globes differing often in this respect by reason of imperfections in their manufacture.

The substantially flat form of the base flange of the chimney permits the flange 95 to be raised closely underneath the upper air chamber of the lantern, thereby reducing the height of the space which is required between the globe and the upper air chamber for the movements of the chimney and 100 its base flange. This also reduces the distance to which the chimney extends below the upper air chamber or lantern top, whereby the height of the lantern is greatly reduced without, however, impairing the 105 burning qualities of the lantern as the flare chamber formed by the globe and the base flange of the chimney is of ample capacity.

The flat base flange can be more readily drawn from sheet metal than a tapering bell, such as is shown in my former patent.

By reducing the height of the lantern 5 several important advantages are gained, among which are reduction of cost of production, reduction of the weight of the lanterns and of the size of the packages in which the lanterns are packed for shipment, 10 reduction of the cost of handling and shipping the lanterns, and reduction of the space required for storing the lanterns in factories, warehouses and stores.

The upper end of the chimney is preferably higher on the front side than on the rear side so that the chimney can yield upwardly slightly on the rear side of the lantern if it should be struck by the globe as the latter is swung forwardly from the 15 tilted position shown in Fig. 2, to the normal position. For that purpose the upper end of the chimney can be made oblique or inclined, as represented at 24 in Fig. 3, or it can be provided on the front side with an 20 upward projection 25, as represented in Fig. 5. The upwardly projecting front portion of the chimney arrests the upward movement of the chimney, as the latter is raised, by striking against a portion 26 in 25 the lantern top, but leaves the rear portion of the chimney free to be raised and the chimney to be slightly tilted if the globe should strike against the base flange of the chimney in being swung forwardly and upwardly toward its normal position, thereby preventing the movement of the globe 30 from being interfered with by the chimney.

I claim as my invention:

1. In a tubular lantern, the combination 40 of a tubular lantern frame, a globe support, a globe resting thereon, a metallic chimney which is movable toward and from the globe and comprises a substantially flat base flange of yielding material to conform 45 to the size and shape of the globe which bears with its marginal portion upon the

globe, and a cranked transverse lifter shaft journaled in said frame, said shaft engaging the chimney above said base flange and having an operating handle at one side of 50 the lantern.

2. The combination with a tubular lantern frame comprising an upper air chamber, a hinged globe support and a globe resting thereon, of a metallic chimney having the upper end thereof located within the air chamber, the said chimney being movable bodily in a substantially vertical direction toward and from the globe and relatively to the air chamber and being 55 provided with means for arresting the upward movement of the chimney at the front side, leaving the rear portion of the chimney free to be raised by a slight tilting movement of the chimney. 60

3. The combination with a tubular lantern frame, a hinged globe support, and a globe resting thereon, of a metallic chimney which is movable in said frame toward and from the globe and which is higher at the 70 front side than at the rear, and a stop in the frame which limits the upward movement of the chimney at the front side.

4. In a tubular lantern, the combination 75 of a tubular lantern frame comprising an upper and a lower air chamber, a globe support, a globe resting thereon, a metallic chimney which is movable toward and from the globe and comprises a substantially flat base flange which bears with its marginal 80 portion upon the globe and is made of yielding material whereby the base flange conforms to variations in size and form of globes, and a cranked transverse lifter shaft between said flange and the upper air 85 chamber.

Witness my hand in the presence of two subscribing witnesses.

WARREN MCARTHUR, JR.
